UNITED STATES PATENT OFFICE

161,357

AWNING OR SIMILAR ARTICLE

Jean McGraw, Los Angeles, Calif.

Application October 31, 1949, Serial No. 5,811

Term of patent 14 years

(Cl. D21—6)

To all whom it may concern:

Be it known that I, Jean McGraw, a citizen of the United States, residing in Los Angeles, in the county of Los Angeles, State of California, have invented a new, original, and ornamental Design for Awning or Similar Article, of which the following is a specification, reference being had to the accompanying drawing, forming a part thereof.

Figure 1 is a front perspective view of an awning or similar article, showing my new design.

Figure 2 is a rear perspective view of the awning shown in Figure 1.

Figure 3 is a side elevational view of the awning.

I claim:

The ornamental design for an awning or similar article, as shown.

JEAN McGRAW.
